UNITED STATES PATENT OFFICE.

HARRY H. SCHUSTER, OF MISHAWAKA, AND DAVID MAIER, OF SOUTH BEND, INDIANA.

SOAP-DISPENSER.

No. 823,446.

Specification of Letters Patent.

Patented June 12, 1906.

Application filed February 4, 1905. Serial No. 244,131.

To all whom it may concern:

Be it known that we, HARRY H. SCHUSTER, residing at Mishawaka, and DAVID MAIER, residing at South Bend, county of St. Joseph, and State of Indiana, citizens of the United States, have invented new and useful Improvements in Soap-Dispensers, of which the following is a specification.

This invention relates to a soap-dispenser, and has for its object to provide a sanitary device of this character from which soap may be dispensed as needed.

The invention consists, broadly, of a non-corrosive receptacle having a stationary cutter for shaving the soap, a spring-pressed follower for holding the soap in contact with the cutter and for rotating the bar of soap against the cutter, and means for supporting the receptacle.

For a full understanding of the invention reference is to be had to the following description and the accompanying drawings, in which—

Figure 1 is a longitudinal vertical section of the device. Fig. 2 is a transverse section on the line *x-x* of Fig. 1. Fig. 3 is a detail in elevation of the follower and spindle, and Fig. 4 is a section on the line *y-y* of Fig. 3.

Making renewed reference to the drawings, wherein similar characters of notation indicate corresponding parts throughout the several views, 1 designates a cylindrical receptacle having a contracted nozzle 2 at its lower end, and fitted upon its top is a cap 3, which preferably screws upon the receptacle. This receptacle is preferably made of glass or porcelain, so as to be non-corrosive, non-porous, and transparent. At the juncture of the nozzle and the cylindrical receptacle is a ledge 4, on which is mounted a stationary cutter 5, which consists of notched bars that cross each other. The teeth 6, formed by the notches, are arranged so that the cut formed by the teeth of one bar will be traversed by the notches of the other bar.

7 designates a bar of soap of such diameter as to freely rotate within the receptacle and be scraped by the teeth of the cutters.

The cap 3 is pierced at its center by a spindle 8, the lower end of which is hollow to receive a square shank 9 of a follower 10, which is provided on its lower face with lugs 11, that enter the bar of soap, so as to cause the latter to rotate when the follower is rotated.

The square shank 9, fitting in the square bore 55 of the hollow spindle, provides a telescoping connection between the follower and spindle, while the former is held against rotation within the bore of the spindle. The spindle is further provided with longitudinal slots 12, 60 and the shank 9 is provided with a pin 13, that plays in the slot and limits the downward movement of the follower by engaging with the end of the slot, as shown in dotted lines in Fig. 1. The play of the follower in 65 the hollow spindle is such as to permit a coil-spring 14, that surrounds the spindle, to force the follower and soap against the cutter when the follower and soap are rotated; but the engagement of the pin with the bottom 70 of the slot will prevent the follower from engaging the cutter when the receptacle becomes empty, and thus the teeth of the cutters are prevented from becoming dull. On the projecting end of the spindle 8 is a crank- 75 handle 15, secured by a screw 16.

The receptacle is supported in a suitable bracket 17, which comprises the upright 18, that may be fixed in any suitable support and clamped thereto by a nut and washer 19. 80 This upright at its upper end is bent at right angles to provide an arm 20, which is curved in a semicircle, as at 21, and has pivoted to its end, as at 22, a corresponding semicircular clasping-arm 23, that carries a thumb-nut 24, 85 adapted to pierce the arm 20, as shown. On the receptacle 1 is an annular protuberance 25, which forms a stop for the dispenser when inserted in the bracket, as shown in Fig. 1. 90

From the above description it will be seen that when the cap 3 is unscrewed and removed from the receptacle the spindle and follower carried thereby may be extracted from the receptacle and a bar of soap may be 95 inserted. The follower, spindle, and cap may now be replaced, and the lugs 11 of the follower will by the action of the coil-spring enter the bar of soap, and when the crank-handle 15 is rotated it will rotate the spindle, 100 follower, and bar of soap, causing the lower face of the last to be scraped by the stationary cutters, which will shave off small particles of the soap, that will be discharged through the nozzle 2. As the soap is cut 105 away it will be continually forced in contact with the cutters by the coil-spring forcing the shank of the follower and the pin carried

thereby out of the hollow spindle and down the slot thereof, respectively. It will further be seen that the pin 13 forms a connection between the follower and spindle and holds the parts intact when they are removed.

Having thus described our invention, what we claim, and desire to secure by Letters Patent, is—

10. 1. A soap-dispenser comprising a receptacle, a follower provided with a shank located in said receptacle, a hollow spindle embracing said shank and having a longitudinal slot, a pin carried by the shank and playing in the slot of the spindle, in combination with a spring surrounding the spindle and bearing against the follower to project its shank from the hollow spindle, and means for rotating the follower.
15. 2. A soap-dispenser comprising a receptacle having a contracted discharge-nozzle, a cutter mounted therein above the nozzle, a spring-pressed follower to hold the soap in contact with the cutter, a hollow spindle having a longitudinal slot, a shank on the follower telescoping within the spindle and having a pin playing in the slot, and a handle on the spindle to rotate the follower and soap.
20. 3. A soap-dispenser of the class described,

comprising a glass receptacle having an integral contracted nozzle at its lower end and a ledge at the top of the nozzle, a stationary cutter resting on the ledge, a cap to close the top of the receptacle, a rotatable spindle mounted in said cap, a follower having a shank telescoping in the spindle and rotatable therewith, a spring surrounding the spindle to hold the follower in contact with the soap, the follower having means to penetrate the soap so as to rotate therewith, and means to support the receptacle.

4. A soap-dispenser comprising a receptacle, a follower provided with a shank located in the receptacle, a hollow spindle embracing said shank and having a longitudinal slot, a pin carried by the shank for movement in the said slot, and a non-rotatable cutter in the receptacle.

In testimony whereof we affix our signatures in presence of two subscribing witnesses.
